UNITED STATES PATENT OFFICE.

PHILIP SILBERHARTZ, OF BROOKLYN, NEW YORK, ASSIGNOR TO MAJESTIC LAMP WORKS, OF NEW YORK, N. Y., A PARTNERSHIP CONSISTING OF SAID SILBERHARTZ, JACOB SILBERHARTZ, AND HARRY SCHEINER, ALL OF BROOKLYN, NEW YORK.

DESIGN FOR A LAMP BASE OR ARTICLE OF ANALOGOUS NATURE.

Application filed June 9, 1928. Serial No. 27,065. Term of patent 3½ years.

To all whom it may concern:

Be it known that I, PHILIP SILBERHARTZ, a citizen of the United States of America, and a resident of the city of Brooklyn, county of Kings, and State of New York, have invented a new, original, and ornamental Design for a Lamp Base or Article of Analogous Nature, of which the following is a specification, reference being had to the accompanying drawing, forming a part hereof.

The single figure of the drawing shows a perspective view of the lamp base or article of analogous nature.

I claim:

The ornamental design for a lamp base or article of analogous nature substantially as shown.

PHILIP SILBERHARTZ.
